UNITED STATES PATENT OFFICE.

WALTER J. RICHARDS, OF MILWAUKEE, WISCONSIN.

FLUID-PRESSURE REGULATOR.

No. 843,083.

Specification of Letters Patent.

Patented Feb. 5, 1907.

Application filed April 7, 1904. Serial No. 202,012.

To all whom it may concern:

Be it known that I, WALTER J. RICHARDS, residing in Milwaukee, in the county of Milwaukee and State of Wisconsin, have invented new and useful Improvements in Fluid-Pressure Regulators, of which the following is a description, reference being had to the accompanying drawings, which are a part of this specification.

This invention relates to certain new and useful improvements in fluid-pressure regulators, and has for its object to provide certain novel means for maintaining a given range of fluid-pressure in fluid-pressure systems by automatically starting and stopping the motor-compressor at predetermined minimum and maximum pressures in the fluid-pressure system.

A further object of this invention is to accomplish the above result by means substantially as the following: A solenoid-operated main switch for the motor-circuit whose solenoid is energized and deenergized indirectly by means of a primary switch sensitive to the pressure of the fluid-pressure system, said primary switch coöperating with motor-starting and supplemental switches, the motor-starting switch for energizing the solenoid of the main switch serving to short-circuit the primary switch and its own actuating-solenoid and the supplemental switch for deenergizing the solenoid of the main switch serving to short-circuit said solenoid of the main switch.

Whereas heretofore devices for somewhat similar purposes have been provided with a primary switch, which, though making only a weak touching contact, is relied upon to carry a heavy current for starting the motor and which is only short-circuited on the completion of the operation of the main switch, it is one of the principal objects of this invention to relieve the primary switch of the necessity for carrying more than a very small amount of current, insufficient for the operation of the motor and even for the operation of the main switch by providing motor-starting and supplemental switches which alone are actuated by the contacts made by the primary switch and which have the function of energizing and deenergizing the solenoid of the main switch.

Another object of this invention is to produce a motor-starting switch for energizing

the solenoid of the main switch having means for holding it closed until the main switch has completed its operation.

With the above and other objects in view the invention consists in the devices and parts and their equivalents to be hereinafter set forth.

In the accompanying drawing the figure represents a diagram of a system for automatic control of motor-compressors exemplifying this invention.

In this drawing, 1 represents a line-wire, which is here shown to be of a grounded circuit, but which may equally well be for a metallic circuit, and 2 is a wire connecting it with the solenoid 3 of a main or motor switch 4, the solenoid 3 being connected to a contact 5, which is engaged by the switch 4 when its solenoid is energized. Another contact 6 is engaged at the same time by the switch 4 and is connected with said contact 5 by means of the switch 4 when the switch is closed and is connected by means of a wire 7 with a motor-compressor 8, which has its other terminal connected by a wire 9 with the ground.

A wire 10 connects the contact 5 with a high-resistance solenoid 11 of a motor-starting switch 12, and a wire 13 connects the solenoid 11 with the minimum contact-point 14 of a primary switch 15. This primary switch has a contact-arm 16 capable of movement toward and away from the contact 14 as the result of varying pressure in a Bourdon tube 17, connected with the fluid-pressure system, and said arm 16 is connected by a wire 18 with a wire 19, which extends from a contact 20 of the motor-starting switch 13 to the wire 7, where it connects with the motor 8.

More in detail, the primary switch 15 comprises the Bourdon tube 17, with its movable end connected by a link 21 with an arm of a pivoted segmental gear 22, which meshes with a pinion 23, carried by the contact-arm 16, so that as the Bourdon tube expands and contracts, due to the variations in pressure in the fluid-pressure system, the contact-arm 16 is caused to move between the minimum contact 14 and a maximum contact 24, which contacts are capable of adjustment in an arc-shaped slot 25 to regulate the connections of the contact-arm 16 with the contacts 14 and 24 so as to take place at predetermined minimum and maximum pressures in the fluid-pressure system.

2
A contact 26 is adapted to be connected with the contact 20 when the motor-starting switch 12 is closed and has connected to it a low-resistance series switch-retaining solenoid 27, affecting the core of solenoid 11 and also connected to the wire 10. It is not necessary for the proper operation of the retaining-coil that it should be connected as above described, as the solenoid 11 may have any other connection so long as the contact made by the arm 16 with the contact 14 completes a circuit therethrough to operate the motor-starting switch 12.

A wire 28 connects the maximum contact 24 of the primary switch 15 with a solenoid 29 of a supplemental switch 30, which solenoid is also connected by a wire 31 to the ground, and a contact 32, connected by a wire 33 to wire 10, is adapted to be connected by the supplemental switch 30 when in its closed position to a contact 34, which is connected by a wire 35 to the line-wire 1.

The operation of the system is as follows: When the fluid-pressure in the fluid-pressure system reaches the minimum, the contact-arm 16 of the primary switch engages with the minimum contact 14 and completes a primary circuit from the line-wire 1 by way of wire 2 and solenoid 3, through wire 10, solenoid 11, and wire 13 to contact 14, and by the contact-arm 16 in engagement therewith, wires 18 and 19, through the motor 8 and wire 9 to the ground. The current through this primary circuit is comparatively small by reason of the fact that said circuit includes the high resistance of the solenoid 11 of the motor-starting switch 12 and is insufficient for the purpose of actuating the main switch 4, though it is capable of closing the motor-starting switch 12. The closing of the motor-starting switch 12 has the effect of short-circuiting the primary-switch connection above mentioned to prevent its arcing and also short-circuiting the solenoid 11 of such motor-starting switch, but establishes a motor-starting circuit through the series switch-retaining coil 27, which will hold the motor-starting switch 12 in engagement with the contacts 26 and 20, notwithstanding the short-circuiting of solenoid 11, until the main switch completes its closing, when the series coil 27 is short-circuited by the main switch. Another function accomplished by the closing of the motor-starting switch 12 is by the short-circuiting of the resistance of the solenoid 11 and the connection of the primary switch to pass a greater amount of current through the main-switch solenoid 3 and cause the closing of the main switch 4, which the current of the initial circuit was incapable of doing. When the main switch 4 is closed, the solenoid 27 is short-circuited, allowing the motor-starting switch to open, and the motor-circuit is established from line-wire 1 through wire 2 and solenoid

3 of the main switch, across the main switch 4 from contact 5 to contact 6, through wire 7 and motor 8 and by wire 9 to the ground. The motor-compressor 8 is started in its operation on the completion of the motor-starting circuit by means of the motor-starting switch and continues in its operation after the closing of the main switch, increasing the fluid-pressure in the fluid-pressure system until the main switch is opened by the primary switch indicating the maximum pressure in the fluid-pressure system by means to be now described. When the pressure in the fluid-pressure system reaches the maximum for which the primary switch is set, the contact-arm 16 engages with the maximum contact 24 and completes a circuit through the solenoid 29 of the supplemental switch 30 by current passing from wire 7 through wire 19 and 18 to the contact-arm 16 and the contact 24 engaged thereby by way of wire 28 to the solenoid 29 and from there by wire 31 to the ground. This has the effect of closing the supplemental switch 30 to produce the short-circuiting of the main-switch solenoid 3 by connecting the contact 5 thereof with the line-wire 1 by way of wires 10 and 33 across the supplemental switch 30 in engagement with the contacts 32 and 34 and by wire 35. The solenoid 3 of the main switch 4 being short-circuited, said switch opens and breaks all circuits, so that the system is restored to its original condition, the motor-compressor 8 coming to rest until the pressure in the fluid-pressure system again reaches the minimum, when the operation above described is repeated.

A prime object of the motor-starting switch is to enable the full flow of current to pass through said motor-starting switch between the time of its closing and the time of the operation of the main switch, so that if for any reason the main switch is not closed immediately the motor-compressor will be started by the motor-starting switch and kept in operation until the main switch closes. This being true, should the primary switch make its minimum-pressure contact at a time when the current upon the motor is insufficient to close the main switch the motor-starting switch will nevertheless close a circuit through the motor to start the motor in operation and continue this function until the current upon the motor rises sufficiently to operate the main switch.

With the existing apparatus previously referred to in this specification, in which the primary switch is relied upon to effect the operation of the main switch without the co-operation therewith of a motor-starting switch, the operation of the primary switch, due to the minimum pressure in the fluid-pressure system at a time when the current upon the motor is insufficient to operate the main switch, will cause the full flow of cur-

rent to be carried by the frail primary switch and produce arcing at such switch because of the primary switch leaving the minimum contact, an objection obviously overcome by the present construction employing the motor-starting switch.

Inasmuch as the motor-starting switch does not draw an arc on opening because of being short-circuited by the main switch and the supplemental switch does not draw an arc when opening because of the current therethrough being broken by the main switch, these switches do not have to be given much movement to accomplish their functions, and consequently less wire may be used in their solenoids than would be possible if sufficient movement were necessary for them to break the current. The only switch in this present system which is relied upon to break the current is the main switch, and as its solenoid is wound for connection in series with the motor it is of large and comparatively inexpensive wire. Therefore with this system no expensive coils are necessary.

While I have shown and described the supplemental switch 30 as adapted to short-circuit the solenoid 3 of the main switch to open said main switch, it is obvious that this supplemental switch may be relied upon to accomplish the opening of the main switch in other ways.

In view of the above I do not limit myself to the application of this system to any particular form of compression means operated by the system or to a compression means at all, for it is also obvious that this system is applicable to other purposes than that for which it has been described and may be relied upon for automatically supplying electric current for any purpose where automatic control is desired from the influence of any equivalent of the primary switch, which is capable of making contacts as the result of changing conditions.

Notwithstanding the recital in the claims of anything contrary to the broad interpretation of said claims to cover the application of the invention for any purpose to which it is applicable it is to be understood that these claims are not to be limited to any particular application of the invention.

Though the circuit established by the primary switch at the minimum contact includes the motor and the magnet of the main switch, the current passing through such circuit is so weak as to be entirely incapable of producing the operation of the motor or even of the main switch, and consequently when later the motor-starting switch closes a circuit through these devices which is capable of producing their operation this circuit is referred to as the "motor-starting" circuit and is said to be closed by the motor-starting switch, and also when the main switch is

closed to establish the normal operating-circuit of the motor this circuit is referred to as the "motor-circuit."

The motor-starting switch-contacts are practically in multiple or shunt connection with the contacts of the main switch, since the resistance of the series coil 27 of the motor-starting switch-magnet included in the circuit established by the closing of the former is so slight as to be insignificant, and the flow of current through the motor caused by the closing of the motor-starting switch is practically the same as the flow of current through the motor when the main switch is closed. Therefore when the contact of the motor-starting switch is referred to as being practically in multiple or in shunt with the contact of the main switch it is to be understood that by this is intended to exclude constructions wherein the resistance in the circuit established by one contact is so much greater than the resistance in the circuit established by the other contact as to be appreciable in the operation of the motor as with motor-starting resistances.

What I claim as my invention is—

1. In a system for controlling an electric motor, a primary switch, a motor-starting switch having its magnet in the circuit controlled by the primary switch, and a main switch having its magnet in the circuit controlled by the motor-starting switch, the contacts of the motor-starting switch being connected practically in shunt with the contacts of the main switch without appreciable intervening resistance.

2. In a system for controlling an electric motor, a primary switch, a motor-starting switch having its magnet in the circuit controlled by the primary switch, a main switch having its magnet in the circuit controlled by the motor-starting switch, and a means influenced by the primary switch for affecting the operation of the main switch, the contacts of the motor-starting switch being connected practically in shunt with the contacts of the main switch without appreciable intervening resistance.

3. In a system for controlling an electric motor, a primary switch, a motor-starting switch having its magnet in the circuit controlled by the primary switch, a main switch having its magnet in the circuit controlled by the motor-starting switch, the contacts of the motor-starting switch being practically in shunt connection with the contacts of the main switch without an appreciable intervening resistance, and a supplemental switch having its magnet connected in another circuit controlled by the primary switch and adapted to cause the opening of the main switch.

4. In a system for controlling an electric motor, a main switch for controlling the motor-circuit, a motor-starting switch for clos-

- ing a circuit through the motor having its magnet in a shunt-circuit around the main-switch-contact, and a primary switch in said shunt-circuit adapted to make a connection 5 to operate the motor-starting switch, said motor-starting switch by its operation being adapted to operate the main switch.
5. In a system for controlling an electric motor, a main switch for controlling the motor-circuit, a motor-starting switch having its magnet in a shunt-circuit across the main-switch contacts, and a primary switch in said shunt-circuit adapted to make a connection 10 to cause the operation of the motor-starting switch, said motor-starting switch by its operation being adapted to short-circuit its own magnet, and the primary-switch connection and thereby effect the operation of the main switch.
- 15 6. In a system for controlling an electric motor, a main switch for controlling the motor-circuit, a motor-starting switch having its magnet in a shunt-circuit around the main switch, a retaining-coil for the motor-starting switch, and a primary switch in said shunt-circuit adapted to make a connection 20 to operate the motor-starting switch, said motor-starting switch by its operation being adapted to short-circuit its own magnet and the primary switch but including in the shunt-circuit the retaining-coil for the motor-starting switch.
- 25 7. In a system for controlling an electric motor, a main switch for controlling the motor-circuit, a motor-starting switch having its magnet in a shunt-circuit around the main switch, a low-resistance retaining-coil for the motor-starting switch, and a primary switch in said shunt-circuit adapted to make 30 a connection to operate the motor-starting switch, said motor-starting switch by its operation being adapted to short-circuit its own magnet and the primary-switch connection, the low-resistance retaining-coil being included in the shunt-circuit while the motor-starting switch is operated, said motor-starting switch adapted to be held in its operated position by said retaining-coil until the main switch completes its operation.
- 35 8. In a system for controlling an electric motor, a main switch for controlling the motor-circuit, a motor-starting switch having its magnet in a shunt-circuit around the main switch, a low-resistance retaining-coil for the motor-starting switch, and a primary switch in said shunt circuit adapted to make 40 a connection to operate the motor-starting switch, said motor-starting switch by its operation being adapted to short-circuit its own magnet and the primary-switch connection by means of the low-resistance retaining-coil and adapted to be held in its operated position by said retaining-coil until the main switch completes its operation, the operation 45
- 50 of the main switch serving to short-circuit the retaining-coil to render the motor-starting switch inoperative and also serving to close the motor-circuit with the main-switch magnet included therein.
- 55 9. In a system for controlling an electric motor, a main switch for controlling the motor-circuit, a primary switch capable of causing the operation of the main switch, and a supplemental switch actuated by the primary switch for rendering the main switch 60 inoperative by short-circuiting its magnet, the magnet of said supplemental switch being in shunt with the motor.
- 65 10. In a system for controlling an electric motor, a main switch for controlling the motor-circuit, a primary switch capable of causing the operation of the main switch, and a supplemental switch actuated by the primary switch for short-circuiting the magnet of the main switch and thereby rendering the 65 main switch inoperative.
- 70 11. In a system for controlling an electric motor, a main switch for controlling the motor-circuit, a motor-starting switch having its magnet in a shunt-circuit around the main switch contact, a primary switch in said shunt-circuit adapted to make a connection 75 to operate the motor-starting switch, said motor-starting switch by its operation adapted to operate the main switch, and a supplemental switch operated by a different connection made by the primary switch and adapted to render the main switch inoperative.
- 80 12. In a system for controlling an electric motor, a main switch for controlling the motor-circuit, a motor-starting switch having its magnet in a shunt-circuit around the main switch contact, a primary switch in said shunt-circuit adapted to make a connection 85 to operate the motor-starting switch, said motor-starting switch by its operation adapted to short-circuit its own magnet and the primary-switch connection and effect the operation of the main switch, and a supplemental switch operated by a different connection 90 made by the primary switch and adapted to short-circuit the main-switch magnet and thereby render the main switch inoperative.
- 95 13. In a system for controlling an electric motor, a main switch for controlling the motor-circuit, a motor-starting switch having its magnet in a shunt-circuit around the main switch, a primary switch in said shunt-circuit adapted to make a connection to operate 100 the motor-starting switch, said motor-starting switch by its operation adapted to short-circuit its own magnet and the primary-switch connection and to energize the main-switch magnet and thereby operate the main switch, and a low-resistance retaining-coil 105 for the motor-starting switch adapted to be included in the circuit established by the op- 110
- 115
- 120
- 125

eration of the motor-starting switch and hold said switch in its operated position until the main switch completes its operation.

14. In a fluid-pressure system, a controller for the motor-compressor thereof comprising a motor-circuit, a main switch for controlling the motor-circuit and having its magnet contained in said motor-circuit, a shunt-circuit around the main switch, a primary switch sensitive to the pressure of the fluid-pressure system adapted to close said shunt-circuit, a motor-starting switch having its operating-magnet included in the shunt-circuit, a retaining-coil of low-resistance for the motor-starting switch, said motor-starting switch adapted to be operated on the closing of the shunt-circuit by the primary switch and when operated adapted to short-circuit its own operating-magnet and the connection made by the primary switch and substitute in the shunt-circuit the low-resistance retaining-coil, the operation of the motor-starting switch also being adapted to energize the main-switch magnet to operate the main switch, said main switch when operated adapted to complete the motor-circuit and short-circuit the retaining-coil of the motor-starting switch, and a supplemental switch having its operating-magnet connected in shunt with the motor-compressor and controlled by another connection made by the primary switch and adapted in its operation to short-circuit the main-switch magnet.

15. In a system for controlling an electric motor, a main switch for controlling the motor-circuit, a motor-starting switch having its magnet in a shunt-circuit around the main switch and in series with the main-switch magnet, and a primary switch in said shunt-circuit adapted to make a connection to operate the motor-starting switch, said motor-starting switch by its operation being adapted to operate the main switch.

16. In a system for controlling an electric motor, a main switch for controlling the motor-circuit, a motor-starting switch having its magnet in a shunt-circuit around the main switch and in series with the main-switch magnet, and a primary switch in said shunt-circuit adapted to make a connection to operate the motor-starting switch, said motor-starting switch by its operation being adapted to short-circuit its own magnet and the primary-switch connection and thereby effect the operation of the main switch.

17. In a system for controlling an electric motor, a main switch for controlling the motor-circuit, a motor-starting switch having its magnet in a shunt-circuit around the main switch and in series with the main-switch magnet, a retaining-coil for the motor-starting switch, and a primary switch in said shunt-circuit adapted to make a connection to operate the motor-starting switch, said motor-starting switch by its operation being

adapted to short-circuit its own magnet and the primary switch and include in the shunt-circuit the retaining-coil for the motor-starting switch.

18. In a system for controlling an electric motor, a main switch for controlling the motor-circuit, a motor-starting switch having its magnet in a shunt-circuit around the main switch and in series with the main-switch magnet, a low-resistance retaining-coil for the motor-starting switch, and a primary switch in said shunt-circuit adapted to make a connection to operate the motor-starting switch, said motor-starting switch by its operation being adapted to short-circuit its own magnet and the primary-switch connection, the low-resistance retaining-coil being included in the shunt-circuit while the motor-starting switch is operated, said motor-starting switch adapted to be held in its operated position by said retaining-coil until the main switch completes its operation as the result of the increased current passed through its magnet due to the short-circuiting of the resistance of the motor-starting-switch magnet.

19. In a system for controlling an electric motor, a main switch for controlling the motor-circuit, a motor-starting switch having its magnet in a shunt-circuit around the main switch and in series with the main-switch magnet, a low-resistance retaining-coil for the motor-starting switch, and a primary switch in said shunt-circuit adapted to make a connection to operate the motor-starting switch, said motor-starting switch by its operation being adapted to short-circuit its own magnet and the primary-switch connection by means of the low-resistance retaining-coil and adapted to be held in its operated position by said retaining-coil until the main switch completes its operation, the operation of the main switch serving to short-circuit the retaining-coil to render the motor-starting switch inoperative and also serving to close a circuit through the motor with the main-switch magnet included therein.

20. In a system for controlling an electric motor, a main switch for controlling the motor-circuit, a motor-starting switch having its magnet in a shunt-circuit around the main switch and in series with the main-switch magnet, a primary switch in said shunt-circuit adapted to make a connection to operate the motor-starting switch, said motor-starting switch by its operation adapted to operate the main switch, and a supplemental switch operated by a different connection made by the primary switch and adapted to render the main switch inoperative.

21. In a system for controlling an electric motor, a main switch for controlling the motor-circuit, a motor-starting switch having its magnet in a shunt-circuit around the main switch and in series with the main-switch magnet, a primary switch in said shunt-cir-

6

cuit adapted to make a connection to operate the motor-starting switch, said motor-starting switch by its operation adapted to short-circuit its own magnet and the primary-switch connection and thereby effect the operation of the main switch, and a supplemental switch operated by a different connection made by the primary switch and adapted to short-circuit the main-switch magnet and thereby render the main switch inoperative.

22. In a system for controlling an electric motor, a main switch for controlling a motor-circuit, a motor-starting switch having its magnet in a shunt-circuit around the main switch and in series with the main-switch magnet, a primary switch in said shunt-circuit adapted to make a connection to operate the motor-starting switch, said motor-starting switch by its operation adapted to short-circuit its own magnet and the primary-switch connection to increase the amount of current flowing through the main-switch magnet and thereby operate the main switch, and a low-resistance retaining-coil for the motor-starting switch adapted to be included in the circuit established by the operation of the motor-starting switch and hold said switch in its operated position until the main switch completes its operation.

23. In a fluid-pressure system, a controller for the motor-compressor thereof comprising a motor-circuit, a main switch for controlling the motor-circuit and having its magnet contained in said motor-circuit, a shunt-circuit around the main switch and in series with the main-switch magnet, a primary switch sensitive to the pressure of the fluid-pressure system adapted to close said shunt-circuit, a motor-starting switch having its operating-magnet included in the shunt-circuit, a retaining-coil of low resistance for the motor-starting switch, said motor-starting switch adapted to be operated on the closing of the shunt-circuit by the primary switch and when operated adapted to short-circuit its own operating-magnet and the connection made by the primary switch and substituting in the shunt-circuit the low-resistance retaining-coil, the removal of the resistance of the motor-starting-switch operating-magnet being adapted to effect the operation of the main switch, said main switch when operated adapted to complete a circuit through the motor and short-circuit the retaining-coil of the motor-starting-switch, and a supplemental switch having its operating-magnet connected in shunt with the motor-compressor and controlled by another connection made by the primary switch and adapted in its operation to short-circuit the main-switch magnet.

24. In a system for controlling an electric motor, a main switch for controlling the motor-circuit, a motor-starting switch adapted to cause the operation of the main switch and

supply current to the motor for starting its operation, and a primary switch for causing the operation of the motor-starting switch, said motor-starting switch having its contact and magnet practically in shunt connection with the main-switch contact and adapted when caused to be operated by the primary switch to remain in its operated position until the main switch is operated.

25. In a system for controlling an electric motor, a primary switch, a motor-starting switch adapted to be actuated on the operation of the primary switch, and a main switch adapted to be operated on the operation of the motor-starting switch, said motor-starting switch having its magnet practically in shunt with its contact and with the contact of the main switch, whereby it is held in its operated position until the main switch is operated.

26. In a system for controlling an electric motor, a primary switch, a motor-starting switch adapted to be actuated on the operation of the primary switch, and a main switch with its operating-magnet in series with the motor and adapted to be actuated on the operation of the motor-starting switch.

27. In a system for controlling an electric motor, a primary switch, a motor-starting switch relying thereon for its operation, a main switch relying on the motor-starting switch for its operation and having its operating-magnet in series with the motor, and a means influenced by the primary switch for also affecting the operation of the main switch.

28. In a system for controlling an electric motor, a primary switch, a motor-starting switch adapted to be closed by the operation of the primary switch, a main switch adapted to be closed by the closing of the motor-starting switch and having its operating-magnet in series with the motor, and a supplemental switch adapted to be operated by a different operation of the primary switch to cause the opening of the main switch.

29. In a system for controlling an electric motor, a main switch for controlling the motor-circuit having its operating-magnet in series with the motor, a motor-starting switch having its magnet in a shunt-circuit around the main-switch contacts, and a primary switch in said shunt-circuit adapted to make a connection to cause the operation of the motor-starting switch, said motor-starting switch by its operation being adapted to cause the operation of the main switch.

30. In a system for controlling an electric motor, a main switch for controlling the motor-circuit having its operating-solenoid in series with the motor, a motor-starting switch having its magnet in a shunt-circuit around the main-switch contact, and a primary switch in said shunt-circuit adapted to make a connection to operate the motor-starting

switch, said motor-starting switch by its operation being adapted to short-circuit its own magnet and the primary-switch connection and effect the operation of the main switch.

5 31. In a system for controlling an electric motor, a main switch for controlling the motor-circuit having its operating-magnet in series with the motor, a motor-starting switch having its magnet in shunt with the main switch so that the closing of the main switch short-circuits said motor-starting-switch magnet, and a primary switch in said shunt-

circuit adapted to make a connection to energize the motor-starting-switch magnet and cause it to close the motor-starting switch to send an operating-current through the motor and to also energize the main-switch magnet. 15

In testimony whereof I affix my signature in presence of two witnesses.
